UNITED STATES PATENT OFFICE.

MAXIMILIAN CHARLES SCHWEINERT, OF WEST HOBOKEN, NEW JERSEY.

ATTACHMENT FOR WATER-BOTTLE STOPPERS OR THE LIKE.

1,424,740.

Specification of Letters Patent. Patented Aug. 1, 1922.

Application filed September 12, 1916. Serial No. 119,619.

To all whom it may concern:

Be it known that I, MAXIMILIAN CHARLES SCHWEINERT, a citizen of the United States of America, residing in West Hoboken, in 5 the county of Hudson and State of New Jersey, have invented certain new and useful Improvements in Attachments for Water-Bottle Stoppers or the like, of which the following is a specification.

10 This invention relates to attachments for water bottle stoppers and aims to provide certain improvements therein.

The invention is particularly directed to a retainer for water bottle stoppers by 15 means of which the stopper is prevented from being lost or misplaced. According to the preferred form of the invention the stopper is provided with a ring of wire which is adapted to encircle the handle or 20 other part of the stopper in such a way that the stopper may turn independently in order to be screwed into the bottle or unscrewed therefrom. Such ring is preferably formed with an integral shank or arm 25 which is adapted to engage a member attached to the funnel of the bag. In its preferred form such member is constructed with a guideway which permits the arm to 30 slide downwardly and upwardly during the application and removal of the stopper, the guideway preferably leading from the inner side of the funnel around to the outer side thereof whereby when the stopper is removed it may conveniently hang on the outer 35 side of the funnel while the bag is being filled.

The invention illustrates other features of improvement which will hereinafter be more fully described.

40 Referring to the drawings which illustrate the preferred form of the invention,—

Figure 1 is a view of the upper part of a water bag showing a neck and funnel in section and showing the stopper and retainer in elevation;

Fig. 2 is a view at right angles to Fig. 1, showing the clip member in elevation;

Fig. 3 is a perspective view showing the retainer and clip member attached.

45 Referring to the drawings let A indicate the body of a water bag having a neck portion B and a funnel portion C. Attached to the neck portion B and vulcanized therein is a socket member D within which screws 50 a stopper member E. The latter is usually provided with a handle F which customarily

has a neck G of smaller diameter than the top of the handle so that it forms a convenient portion for the engagement of the retainer. The retainer may, however, be 60 swiveled to the stopper in any other way it is desired.

In the preferred form the retainer comprises a ring H formed of metal and having a spring end I (see Fig. 3) by which 65 it may be attached to the neck G. Preferably formed integrally with the ring H is an arm J extending to one side of the ring, the arm being usually slightly bent upwardly, as best shown at Fig. 1.

70 According to the present invention means are provided for connecting the end of the arm J to the water bag and in the construction shown this connection is with the top of the funnel C. Preferably the connection is made with a member K, which is best constructed in the form of a spring clip adapted to frictionally engage the funnel. As illustrated the clip is made of wire bent to appropriate form and having a recess 75 L adapted to fit over the upper end of the funnel, and a ring M lying on one side of the funnel and a spring N lying on the opposite side of the funnel. The function 80 of the end N is to press the wall of the funnel into the ring M, thereby securing a very tenacious grip on the funnel. An important feature of the invention is the provision of a guideway O which, as shown in Fig. 1, 85 preferably extends from a point within the funnel designated by the letter P to a point outside the funnel designated by the letter Q. The end of the arm J is preferably bent around the outside wire of the clip and lies in the guide O so that it is capable of sliding 90 along the latter. This permits an upward and downward movement of the end of the arm J so that the ring H may move upwardly and downwardly with the stopper while the latter is being removed or inserted. 95 Preferably the guideway extends to the top of the funnel and then downwardly so that the stopper may hang over the side when not in use as shown in the dotted lines in Fig. 1.

100 In use, the stopper may be easily screwed into its socket member, the stopper during this operation swiveling within the ring H. When the stopper is removed it is moved outwardly so that the arm J slides along the 110 guide O and assumes the position shown in dotted lines, whereby the stopper is entirely

free from the funnel and does not in any way interfere with the filling of the bottle. The stopper may occupy the same position in emptying the bottle if desired.

5 While I have shown and described one form of the invention it will be understood that I do not wish to be limited thereto since various changes may be made therein without departing from the spirit of the invention. For instance, the exact construction of the retainer may be varied as well as its swiveled connection with the stopper. The clip member K may also be constructed in various forms and of various materials. 10 15 I prefer, however, that described, since it is cheap, simple and easily applied to and removed from the funnel.

What I claim is:—

1. A member having means for detachable connection to the funnel of a hot water bag or the like, and having a guide for a retainer, along which the latter may move, such guide extending along the inner side of the funnel.

25 2. The combination with a retaining member adapted to be detachably connected to a hot water bag stopper or the like, and having a substantially rigid arm, and a member adapted to be connected with the funnel of the bag, said member adapted in one position to permit the stopper to be screwed in its socket, and in another position said arm and stopper to hang freely on the outside of the funnel.

30 3. A member having a spring clip for connecting it to the funnel of a water bag or the like, and having a guide along which a retainer may move, said guide extending from the inside of the funnel toward the top thereof.

35 4. A member formed of wire and having means for embracing the wall of a funnel of a water bag or the like, said member having a guide for a retainer, along which a retainer may move, said guide extending from the inner side of the funnel around the top thereof to the outside thereof.

40 5. A clip for water bags or the like adapted to engage the funnel thereof, said clip having oppositely arranged members adapted to embrace the wall of the funnel, and having a guide for a retainer, along which a retainer may move, said guide extending from the inner side of the funnel over the top thereof to the outside thereof.

45 6. A clip for water bags or the like adapted for connection to the funnel thereof, said clip formed of a single piece of wire and bent to form portions embracing the edge 50 of the funnel, one of said portions being

of substantially ring shape and the other being adapted to press the wall of the funnel into the first, and said clip having means to engage a retainer or stopper.

7. A retainer for water bottle stoppers 65 comprising a rigid member adapted to make a swivel engagement with the water bottle stopper and having an integral arm, and a clip adapted to embrace the edge of the funnel, and having a guide engaged by said arm, and along which the latter may move, said guide extending from the interior of the funnel toward the top thereof.

8. A retainer for stoppers for water bags or the like, comprising a wire member 75 having a ring at one end adapted to loosely engage the handle of the stopper, and having an arm extending from said ring, in combination with a wire clip embracing the funnel of the bag and formed with a guide 80 along which the wire member may move extending from the inner side of the funnel around the top thereof to the outside thereof.

9. A retainer for water bag stoppers or the like, comprising a retainer member 85 formed of a single piece of wire formed with the ring H, adapted to loosely surround the handle of the stopper, an integral arm J in combination with a wire clip adapted to embrace the upper edge of the funnel 90 and having portions M and N adapted to frictionally grip the wall of the funnel, and having a guide engaged by said arm J along which the latter may move and extending from the interior of the funnel over the top 95 thereof to the outside thereof.

10. In a hot water bag, the combination with a stopper having a thumb member of an inflexible connection provided with an annular member at one end to loosely encircle the thumb-member and having an eye at its other end, and means linked to the eye for connection with an unperforated portion of the water bag, said means permitting the connection and stopper to hang 100 loosely over the side of the funnel of the bag.

11. In a hot water bag, the combination with a stopper having a thumb-member of an inflexible connection provided with an 110 annular member at one end to loosely encircle the thumb-member and having an eye at its other end, and means linked to the eye for embracing a portion of the water bag, said means permitting the connection 115 and stopper to hang loosely over the side of the funnel of the bag.

In witness whereof, I have hereunto signed my name.

MAXIMILIAN CHARLES SCHWEINERT.
